LIGHTWEIGHT SADIRON CONSTRUCTION

Howard A. Smith, St. Louis, Mo., assignor to
Knapp-Monarch Company, St. Louis, Mo., a
corporation of Missouri

Application July 16, 1935, Serial No. 31,613

8 Claims. (Cl. 219—25)

An object of my invention is to provide a light weight sad iron construction having parts of simple, durable and inexpensive construction, which are readily assembled and retained in assembly with but very few fastening parts.

A further object is to provide a light weight sad iron construction, comprising a sole plate having a heating element groove, a heating element being provided in the groove and retained in position by a sheet metal plate rather than the usual weight member, so that a light weight iron is thus produced, the sheet metal plate being preferably retained in position by a simple fastening element adjacent its center driven into a socket of the sole plate.

A further object is to provide a single securing means for a shell and a handle on the sole plate.

Still another object is to provide a novel terminal pin assembly, which is assembled under tension relative to the shell and supported thereby and to provide a rest member and protector for the terminal pin, which is also secured under tension to the shell.

With these and other objects in view, my invention consists in the construction, arrangement and combination of the various parts of my light weight sad iron construction, whereby the objects contemplated are attained, as hereinafter more fully set forth, pointed out in my claims, and illustrated in the accompanying drawing, in which:

Figure 1 is a vertical, longitudinal, sectional view through a light weight sad iron embodying my invention.

Figure 2 is a horizontal sectional view on the line 2—2 of Figure 1.

Figure 3 is a sectional view of a portion of Figure 1, showing the parts during assembly, and particularly a terminal assembly being assembled relative to the shell of the iron.

Figure 4 is a similar sectional view showing a terminal pin protector and rest member being assembled relative to the shell of the iron.

Figure 5 is a perspective view of the rear end of the iron showing the rest member in assembled position; and

Figure 6 is a perspective view of a terminal pin supporting member used in my iron.

On the accompanying drawing, I have used the reference numeral 10 to indicate a sole plate. It is provided with a heating element groove 12, in which is a heating element 14 comprising preferably a coiled resistor embedded in refractory material.

The heating element 14 is retained in position by a sheet metal plate 16 which in turn is secured to the sole plate 10 by a headed pin 18. The pin 18 is made of brass or the like, and is 60 a drive fit in a socket 20 of the sole plate 10, so

as to be frictionally held therein after the simple operation of driving it home, instead of having to use screws as in the ordinary manner.

The sole plate 10 is provided with a boss 22 having a threaded socket 24. The sheet metal plate 16 is provided with a perforation 26 through which the boss extends.

A shell 28 is mounted on the sole plate 10 and held in mounted position by a screw 30. The upper end of the screw 30 extends through a perforation 32 in the shell 28 and is screwed into the socket 24.

A handle yoke 34 is provided having a perforation 36 for the screw 30 to extend through. The shell 28 is provided with a pair of perforations 38 into which projections 40 of the handle yoke 34 extend. This prevents the handle yoke from turning relative to the screw 30 and the screw provides a single means for retaining the handle yoke in position. A handle 42 is mounted on the yoke 34.

The sheet metal plate 16 has a pair of perforations 44 in which insulators 46 are located.

The ends 48 of the heating element extend through the insulators 46 and are insulated by them from contact with the sole plate and the sheet metal plate.

The heating element ends 48 are connected with terminal pins 50, which are mounted on and insulated from a terminal pin support A shown in Figure 6. The support A comprises a plate portion 52 dished and terminating in a flange 54. A portion 56 of the flange 54 is displaced so as to provide a yoke-like construction at the front of the support A. The support A also includes an arm 58 terminating in a lug 60.

The shell 28 has a pair of walls indicated at 28a and 28b, which are arranged at an angle relative to each other. The wall 28a is provided with a terminal pin opening 62 closed by the plate portion 52 of the support A when in assembled position and through which the terminal pins 50 extend.

The yoke portion provided by the flange 54 and the offset portion 56 thereof and the lug 60 are initially formed a greater distance apart than the forward edge of the terminal pin opening 62 and a perforation 64 in the wall 28b.

To assemble the support A relative to the shell 28, the yoke portion is first engaged with the front edge of the terminal opening 52 as in Figure 3, and the arm 58 is sprung by a tool indicated at 66 in the direction of the arrow a, so that the lug 60 can enter the perforation 64, and thereafter the arm 58 will spring to its original position, thus placing the parts under tension, so that the terminal pin assembly is rigidly connected with the shell 28.

A terminal pin protector and rest member B is illustrated, comprising a widened foot portion 60

68, an arm portion 10, and side flanges 12 and 74. The flanges 74 terminate in hooked lugs 76 adapted to hook into the perforations 78 of the wall 28a of the shell 28. The flanges 72 are 5 provided with forwardly extending lugs 80 adapted to enter perforations 82 of the wall 28b, by first placing the rest member in the position shown in Figure 4, and then swinging it as indicated by the arrow b until the dotted position of 10 Figure 1 is assumed. Thereafter the widened foot portion 88 is sprung downwardly to the full line position, and the lugs 88 bent over laterally inside the shell to thus connect the rest member under tension with the shell.

15 The angle of the forward and lower edges of the flanges 72 and 74 respectively is slightly less acute than the angle of the walls 28a and 28b as illustrated by the dotted lines in Figure 1 so that when the full line position is assumed, the 20 parts are under tension.

The terminal assembly and rest member, it will be noted, are of simple construction, and the assembly thereof relative to the shell takes but a minimum of time. I am thus able to produce a 25 sad iron which is light in weight and also inexpensive, because assembly of the parts and the material required for the parts is thus reduced to the minimum.

Some changes may be made in the arrangement and construction of the various parts of 30 my light weight sad iron construction, without departing from the real spirit and purpose of my invention, and it is my intention to cover by my 35 claims, any modified forms of structure or use of mechanical equivalents, which may be reasonably included within their scope.

I claim as my invention:

1. In an electric appliance having a heating element and a shell, a terminal assembly for said 40 heating element comprising an elongated plate portion having a pair of terminals thereon and spaced longitudinally thereof, and an arm portion extending from one side thereof and arranged at an angle relative to the plane of said plate portion, 45 the opposite side of said plate portion and the outer end of said arm portion engaging spaced parts of said shell under stress to support said terminal assembly relative to said shell.

2. In an electric appliance having a heating 50 element and a shell, a terminal assembly for said heating element, comprising a plate portion, and an arm portion arranged at an angle relative to each other, opposite ends of said terminal assembly having lugs, said shell having spaced perforations to coat with said lugs, the parts of said 55 perforations with which said lugs coat being spaced closer together than the distance apart of said lugs, whereby said terminal assembly after coaction with said shell remains in coaction therewith under stress.

3. In an electric appliance having a heating 60 element and a shell, a terminal assembly for said heating element, comprising an elongated terminal pin supporting portion, and an arm portion extending from the side of said pin supporting portion, said shell having a terminal pin opening, said terminal pin supporting portion closing said opening and having a portion at its side opposite said arm portion engaging the side of said opening, said 65 shell having another perforation, a portion of said arm coacting with said other perforation to retain 70

said terminal pin assembly supported relative to said shell.

4. In an electric appliance having a heating element and a shell, a terminal assembly for said heating element comprising an arm portion and a dished terminal pin supporting portion having a peripheral flange, a portion of said flange opposite said arm being displaced whereby to form a yoke portion, said shell having a terminal pin opening, said yoke portion receiving the edge of said opening and said terminal pin supporting portion closing the opening, said shell having another perforation, a portion of said arm coacting with said other perforation to retain said terminal pin assembled relative to said shell. 15

5. In an electric appliance having a heating element and a shell, a terminal assembly for said heating element comprising an arm portion and a dished terminal pin supporting portion having a peripheral flange, a portion of said flange opposite said arm being displaced whereby to form a yoke portion, said shell having a terminal pin opening, said yoke portion receiving the edge of said opening and said terminal pin supporting portion closing the opening, said shell 20 having another perforation, a portion of said arm coacting with said other perforation to retain said terminal pin assembled relative to said shell. 25

6. In an electric appliance having a heating element and a shell, a terminal assembly for said heating element comprising a T-shaped stamping having the leg thereof arranged at an angle relative to the plane of the arms thereof, a terminal pin supported by each of said arms, the top of said T-shaped stamping and the lower end of said leg engaging spaced parts of said shell under stress to support said terminal assembly relative to said shell. 30

7. In an electric appliance having a heating element and a shell, a terminal assembly for said heating element comprising a stamping having a pair of portions arranged at an angle relative to each other, terminal pins supported by one of said portions, opposite ends of said terminal assembly having lugs, said shell having spaced perforations to coat with said lugs, the parts of said perforations with which said lugs coat being spaced closer together than the distance apart of said lugs, whereby said terminal assembly after coaction with said shell remains 50 in coaction therewith under stress. 55

8. In an electric appliance having a heating element and a shell, a terminal assembly for said heating element comprising an arm portion and a terminal pin supporting portion, said shell having a terminal pin opening, said terminal pin supporting portion closing the opening, means at the edge of said terminal pin supporting portion for engaging the edge of said opening, said shell having another perforation, a portion of said arm coacting with said other perforation to retain said terminal pin assembly relative to said shell in conjunction with said means engaging the edge of said terminal pin opening. 60 65

HOWARD A. SMITH. 70
